Primary Examiner — Ruth McInroy

(74) *Attorney, Agent, or Firm* — Dorsey & Whitney LLP

(57) **CLAIM**

We claim the ornamental design for a helmet, as shown and described.

DESCRIPTION

FIG. 1 is a front isometric view of a first embodiment of a helmet illustrating a helmet liner and straps for environment. FIG. 2 is a right side view of the helmet of FIG. 1 illustrating the helmet liner, straps, and a fit adjustment mechanism for environment.

FIG. 3 is a rear view of the helmet of FIG. 1 illustrating the helmet liner, straps, and fit adjustment mechanism for environment.

FIG. 4 is a front isometric view of the helmet of FIG. 1.

FIG. 5 is a front view of the helmet of FIG. 1.

FIG. 6 is a rear view of the helmet of FIG. 1.

FIG. 7 is a right side view of the helmet of FIG. 1.

FIG. 8 is a left side view of the helmet of FIG. 1.

FIG. 9 is a top view of the helmet of FIG. 1.

FIG. 10 is a bottom view of the helmet of FIG. 1.

FIG. 11 is a left side view of the helmet of FIG. 1 showing a first group of movable vent shutters in an alternate open position.

FIG. 12 is a top view of the helmet of FIG. 11.

FIG. 13 is a left side view of the helmet of FIG. 1 showing a second group of movable vent shutters in an alternate open position.

FIG. 14 is a top view of the helmet of FIG. 13.

FIG. 15 is a left side view of the helmet of FIG. 1 showing the first and second groups of movable vent shutters each in an alternate open position.

FIG. 16 is a top view of the helmet of FIG. 15.

FIG. 17 is a front isometric view of a second embodiment of a helmet.

FIG. 18 is a front view of the helmet of FIG. 17.

FIG. 19 is a rear view of the helmet of FIG. 17.

FIG. 20 is a right side view of the helmet of FIG. 17.

FIG. 21 is a left side view of the helmet of FIG. 17.

FIG. 22 is a top view of the helmet of FIG. 17; and,

FIG. 23 is a bottom view of the helmet of FIG. 17.

The broken lines are provided for illustrative purposes only and form no part of the claimed design.

1 Claim, 23 Drawing Sheets
